UNITED STATES PATENT OFFICE.

LYMAN O. GOODWIN, OF NORTH ANDOVER, MASSACHUSETTS, ASSIGNOR OF ONE-HALF TO GEORGE L. WRIGHT, OF NORTH ANDOVER, MASSACHUSETTS.

VALVE.

SPECIFICATION forming part of Letters Patent No. 746,955, dated December 15, 1903.

Application filed April 26, 1901. Serial No. 57,589. (No model.)

To all whom it may concern:

Be it known that I, LYMAN O. GOODWIN, a citizen of the United States, residing at North Andover, in the county of Essex and State of Massachusetts, have invented certain new and useful Improvements in Valves, of which the following is a specification, reference being had therein to the accompanying drawings.

10 This invention relates to improvements in valves, and particularly to rotary valves.

One object of the invention is to so construct a valve that the exhaust may be delivered from the end of the valve, while the supply is delivered at a point intermediate the ends.

Another object is to so construct a valve and its casing that the supply-inlet is constantly open, while the exhaust-ports are alternately 20 opened.

Another object of the invention is to so construct a valve that the exhaust may be received at the periphery of the valve and delivered at the end thereof, while the supply 25 is received into that portion of the valve which is intermediate the ends, as well as intermediate the exhausts.

Another object of the invention is to provide a novel and simple rotary valve.

30 This invention consists in a valve having a series of channels open at the periphery of the valve and at one end thereof.

The invention also consists in a valve-casing having an inlet-port, a pair of outlet-ports 35 considerably less in diameter than the inlet-port, and a wall intermediate the outlet-ports, together with a valve having a transverse supply-channel adapted to alternately connect the inlet-port with the respective outlet-ports, 40 and a pair of exhaust-channels having openings in the periphery of the valve and adapted to be brought opposite the corresponding outlet-ports of the casing at times.

The invention also consists in a cylindrical 45 valve having a transverse channel and a series of channels open at the periphery of the valve and at one end thereof.

The invention also consists in such other 50 novel features of construction and combination of parts as shall hereinafter be more fully described, and pointed out in the claim.

Figure 1 represents an elevation of the im-

proved valve and the casing therefor. Fig. 2 represents a longitudinal sectional view taken on line 2 2, Fig. 3. Fig. 3 represents a 55 vertical sectional view of the same, taken on line 3 3, Fig. 2.

Similar numbers of reference designate corresponding parts throughout.

In carrying this invention into practice it 60 has been my main object to provide a rotatable valve whereby a supply might be alternately directed to a plurality of mechanisms and that such mechanisms might be alternately connected, by channels in the valve, 65 with outlets through which the exhaust fluid or gases from said mechanisms is free to pass.

In the drawings, 5 indicates the cylindrical casing, having the annular lip 6 and furnished with the inlet-port 7 and with the 70 outlet-ports 8 and 9, the wall 10 between these ports 8 and 9 being directly opposite the port 7. Rotatably mounted in the casing is the valve 11, having the stem 12, adapted to receive mechanism for causing the rotation of 75 the valve, and furnished with the transverse supply-channel 13, with its enlarged mouth 14, and the exhaust-channels 15 and 16, which have the mouths 17 and 18, corresponding to the respective ports 8 and 9 and extending to 80 the end of the valve. As shown in Fig. 3 of the drawings, the valve is in the closed position. When the valve is rotated in the direction indicated by the arrow, the mouth 18 of the channel 16 is gradually brought 85 opposite the port 9 while the inner end of the channel 13 is brought opposite the port 8. The gas or fluid may now pass through the channel 13 and the port 8 of the casing to the mechanism, while the exhaust from the mechanism connected with the port 9 may pass through this port into the channel 16 and thence through the open end of said channel into any suitable receptacle or into the open air. The rotation of the valve being reversed, 90 the mouth 17 of the channel 15 is brought opposite the port 8 to receive the exhaust from its related mechanism, and the channel 13 is brought opposite the port 9 to deliver a supply of gas or fluid to its related mechanism. 95 The rocking back and forth of the valve thus alternately opening the supply to one mechanism while it opens the exhaust to the other mechanism.

Having thus described my invention, I claim as new and desire to secure by Letters Patent—

The combination with a suitable casing, of a cylindrical valve having a transverse port and an exhaust-port located at each side of the transverse port and extending longitudinally of said valve, said exhaust-ports having curved walls forming the peripheral portions

of the valve and openings extending to the end thereof.

In testimony whereof I affix my signature in presence of two witnesses.

LYMAN O. GOODWIN.
